Inventor:

William F. Hofford;

Robert W. Ladd,

Attorney.

UNITED STATES PATENT OFFICE

WILLIAM F. HOFFORD, OF NEAR MODOC, INDIANA

INTERLOCKING JOINT

Application filed September 8, 1925. Serial No. 55,064.

The object of my present invention, broadly speaking, is to provide an attachment for vehicles, particularly for automobiles, which attachment is to be employed in connection with the running boards of automobiles, said attachment being simple in character, strong and durable in construction, easily operated and controlled, adapted to provide a variety of utilities, and which can be manufactured and sold at a comparatively low price.

More particularly stated, my object is the provision of an attachment for the running boards of automobiles, by which one is enabled to provide a luggage carrier, an elevated table, a single-bed, a double-bed, and various other instrumentalities which may suggest themselves in the course of the following specification.

One way of carrying out the principles of my invention in a practical and mechanical manner is shown in the accompanying drawings, in which—

Figure 1 shows my construction in elevation, as arranged to provide a double-bed. Figure 2 shows the same as arranged to provide a table. Figure 3 is the same as arranged simply for a luggage carrier or side guard. Figure 4 shows the same as arranged when not in use or out of operative position. Figure 5 is a perspective view of the negative head member of one of the interlocking devices. Figure 6 is a perspective view of the positive head member of one of the interlocking devices. Figure 7 is a perspective view of one of the supporting clips. And Figure 8 is an end view of one of the hangers.

Similar indices denote like parts throughout the several views.

In order that the construction, the operation, and the several advantages of my invention may be more fully understood and appreciated, I will now take up a detailed description thereof.

In the drawings letter A denotes the running-board of an automobile, and B denotes

the usual fenders, while C denotes a pneumatic tire which surround the usual ground wheels by which the automobile is supported, and letter D denotes the ground line. Said parts are shown merely to make clear the positions of the several parts of my invention with relation thereto.

Secured to the underside of the running-board A are the two bearings or hangers, 1 and 2. Each of said hangers is secured by a pair of bolts 3 and 4. Slidably and rotatively mounted in said hangers is the relatively heavy rod 5. A set-screw 6 operates in the hanger 1 and it is adapted to engage the rod 5 when it is desired to retain said rod at a certain point.

Surrounding that portion of the rod 5 which projects under the automobile from the bearing 2, is the helical spring 7. The outer end of the spring 7 engages the bearing 2, while its inner end is secured to the innermost end of the rod 5, as by the key 8. Said spring is normally expanded, permitting the rod 5 to be moved outward endwise against the resiliency of said spring and to be automatically returned to normal position when it is released.

The negative member of the head comprises a tubular portion 9 in which fits the outer end of the rod 5, where it is secured by the key 10. Integral with the outer end of the member is the flat portion 11 through which is formed a main slot 12, and a branch slot 13 connected therewith at an angle. From the contact face side of the member 11 project three lugs 14, 15 and 16, as shown in Fig. 5. Said lugs are square in cross section. The lug 14 is located at one side of one end of the slot 12, and the lugs 15 and 16 are located on each side of the other end of said slot. In alignment with the part 11 and extending down from the part 9, is an ear 17, through which is an aperture 18 which is adapted to receive a bolt.

The positive member of the head or inter-

locking joint comprises a plate portion 19, from the contact face of which project three bars: the center bar 20, and the two side bars 21 and 22, which bars are arranged parallel with each other. There is an aperture 23 formed through the plate 19 and the center of the bar 20, all as shown in Fig. 6. Also a hook portion 24 is formed at right-angles to the bar 22 and across the end of the part 19.

10 At the opposite end of the plate 19 from said bars there is a U-shaped groove or cavity 25, formed in the material extending from the face of said plate and integral therewith, which cavity is almost opposite to and spaced from the bar 20, as shown.

15 Integral with and forming a continuation of the plate 19 is the T-bar standard 26. Formed integral with the upper, outer, end portion of the standard 26, on the stem portion thereof, is a double rib 27 extending out on both sides of the stem of said standard; and a similar rib 28 is formed near the junction of the standard with said plate 19.

20 Numeral 29 denotes a bolt which is inserted through the aperture 23 and the slot 12, to secure the positive and the negative members together; the arrangement of said parts being such that the standard may (without its removal) be adjusted at various angles in relation to the rod 5, and by means of said bolt 29 secured at such adjusted position.

25 When secured to the underside of the running-board the device may be folded, as in Fig. 4, where it may be carried when not in use by tightening the bolts 29 and 6, and also as a further precaution a bolt may be secured in the aperture 18 to allow the standard to rest on the head of such bolt which is the aperture 18.

30 Desiring now to use the device as a luggage carrier then the bolt is removed from the aperture 18, and the nut on the bolt 29 is then loosened, after which the standard 26 may be turned to the position in which it is shown in Fig. 3 where the bolt 29 will be in the lower end of the slot 12, and the lugs 15 and 16 will be in the channels formed between the bars 20, 21 and 22, at the same time the lug 14 will be in the cavity 25, thereby securely locking the standard in vertical position, and then by tightening the bolt 29 it will be retained in that position. Or the standard may be similarly secured in horizontal position, as in Fig. 1, in which event 35 the lugs 15 and 16 will be in engagement with the outer edge of the bar 21, while the lug 14 will be in engagement with the outer edge of the bar 22, and also with the hook 24.

40 By reason of the rod 5 being slidably mounted it is evident that the space capacity of the running-board A may be increased, that is luggage which is wider than the running-board may be placed thereon by pulling outwardly on the standard 26, against the resiliency of the spring 7, and then when the

50 said standard is released the spring 7 will cause the standard to press against and hold the luggage in place on the running-board.

55 It is to be understood that a plurality of devices just described which includes the standard 26, are employed and are spaced along the running-board, and all of the standards on each running-board are connected by the angle-bars 30 and 31, and if desired an intermediate flat bar 32.

60 In most instances the devices described are provided in duplicate on each side of an automobile, or the devices normally employed on one side of the automobile are combined with the like devices on the other side of the automobile, this being the case as shown in Figs. 1 and 2 of the drawings. To accomplish this two clips, such as shown in Fig. 7 are employed. Each of the clips consists of a thimble portion 33, which is integral with the projection 34 which has a T-shaped channel 35 therethrough, which channel is adapted to receive the rib 27 or 28, as shown in Figs. 1 and 2. The clips may be secured in connection with the ribs 27 and 28 by inserting 65 a cotter pin or key in the aperture 36.

65 Two of said clips are to be connected with each standard, as shown, and the rod 5 of the second device is then run into the parts 33 of the clips, after which the standards of the second devices may be operated in the same manner as first mentioned, thereby enabling one to provide the double-bed arrangement shown in Fig. 1, or the elevated arrangement shown in Fig. 2. It is also evident that as 70 the standards 26 are pivoted on their bolts 29 the standards and the parts carried thereby may be folded or turned in under the running-board A, when the device is not in use.

75 When constructed as above set forth it is apparent that I am enabled to provide the various arrangements and accomplish the several objects herein set forth, with means whereby the same may be attained in a minimum of time and trouble.

80 What I claim and desire to secure by Letters Patent of the United States, is—

85 In combination with a horizontal rod and a movable standard; an interlocking joint for hinging said rod and standard together whereby they may be locked in various positions with relation to each other, a plate formed integral with the standard, a center bar and two side bars all arranged parallel with each other and projecting from the contact face of said plate with the center bar having an aperture formed therethrough and then continuing through said plate, a hook extending out at right-angles from said plate and from one of said side bars, there being a 90 U-shaped cavity carried by said plate and located opposite to and opening toward said center bar but spaced therefrom, a flat member detachably connected to said rod and having a main slot and a branch slot con-

nected with the main slot at an acute angle with both slots formed through said flat member, a series of three lugs projecting from the contact face of said flat member, 5 said lugs being square in cross section and located near said slots, and a bolt detachably inserted through said aperture in said center bar and through said slots in order to rigidly connect said plate and flat member in various positions with relation to each other.

10 WILLIAM F. HOFFORD.
